UNITED STATES PATENT OFFICE.

SIMON J. HARDING, OF WEST BALDWIN, MAINE.

WASHING-MACHINE.

1,386,495.

Specification of Letters Patent.

Patented Aug. 2, 1921.

Application filed February 10, 1920. Serial No. 357,581.

To all whom it may concern:

Be it known that I, SIMON J. HARDING, a citizen of the United States, residing at West Baldwin, in the county of Cumberland 5 and State of Maine, have invented new and useful Improvements in Washing-Machines, of which the following is a specification.

My present invention has reference to a washing machine.

10 The improvement relates to that class of washing machines which rest directly on a tub and which includes a rubbing board, a vibratory frame carrying a roller which operates with the rubbing board, and a pump 15 plunger contriving motion from the vibratory frame, the said pump being utilized to project water on the fabric operated on by the roller and the rubbing board.

20 A further object of the invention is to simplify the existing art by providing a washing machine of this character wherein an apron is provided for preventing the splashing of the water but which is susceptible to an outward movement when contacted by 25 the oscillatory frame and closed by means associated with the pump plunger that is also provided by the oscillatory frame, and in addition to this to provide means for automatically engaging and locking the oscillatory frame to permit of the proper arrangement 30 of clothes on the rubbing board.

The foregoing objects and others which will appear as the nature of the invention is better understood, may be accomplished 35 by a construction, combination and operative arrangement of parts such as is illustrated by the drawings.

In the drawings:—

Figure 1 is a side elevation of the improvement.

Fig. 2 is a top plan view thereof.

Fig. 3 is a sectional view approximately on the line 3—3 of Fig. 2.

Fig. 4 is a view illustrating the manner in 45 which the oscillatory frame is held against movement as when clothes are to be arranged on the rubbing board.

Fig. 5 is a view showing the manner in which the spring associated with the pump 50 rod exerts a pressure against the hinged apron to swing the same closed and prevent outward splashing of water from the pump.

In the drawings the numeral 1 designates 55 an ordinary washing tub. On this tub rests the base of the improvement. The base preferably comprises spaced end mem-

bers 2 having an outwardly inclined board 3 connecting the same adjacent to one end of the base and a vertical straight board 4 connecting the members 2 adjacent to the 60 opposite end of the base. The side members 2 have their lower edges notched, the walls provided by the said notches are rounded so that the said notches will snugly engage with the staves of the tub 1. To 65 the board 4 there is secured a downwardly extending pump-barrel 5. In the pump barrel is a piston 6. To the piston is secured a piston rod 7.

Arising from the side members 2 of the 70 base are opposed uprights 8. These uprights, adjacent their outer ends are slotted as at 9, and the said outer ends of the uprights are connected by a rod 10.

Received in the slots 9 are guide trunnions 75 11, on the upper end of the oscillatory frame 12. The frame 12, at the lower end thereof has journaled between its side members the shaft of a ribbed roller 13, while above the roller and supported between the sides of 80 the oscillatory frame is a soap holding member having an open bottom for delivering soap or a soap powder to the roller 13. The roller 13 co-engages with a ribbed rubbing board 14 secured on the base between 85 the sides 2 thereof.

Secured to the trunnions 11 are springs 15 that are also secured to the outer faces of the uprights 8.

On the lower end of the oscillatory frame 90 are upwardly inclined arms 16 connected by a round rod 17 that provides the operating handle for the frame.

On the member 12 of the frame there is centrally secured an outwardly extending 95 arm 18 having a slotted outer end 19 and in the slot of the said end there is a pivot 20 whereby the piston rod 7 is connected to the arm 18, and also whereby the plunger receives motion by the oscillation of the 100 frame. The spout for the pump is indicated by the numeral 21 and is arranged to the rear of and slightly above the rubbing board 14. It will be apparent that were deflecting means not provided the water from the spout 105 would splash upwardly and out of the device, the water being ejected during operation of the device. This only directs the water downwardly, and therefore hingedly secure, as at 21 to the inner edge of the 110 member 2 an apron 22. This apron has its inner edge provided with an upturned lip

23 designed to be contacted by the roller but incident to the shape thereof free from injury by such contact. Such contact however will swing the apron open. To close 5 the apron I provide on the plunger rod 7 a curved spring 24 which contacts with the lip 23 of the apron and exerts a tension thereagainst to cause the apron to be swung to closed position and to retain the said 10 apron in closed position. The movement of the oscillatory frame in a direction away from the pump is limited by stop means 25 on the sides 2 of the frame, and in order to lock the frame when the same is brought 15 toward the end 4 of the base and out of engagement with the rubbing surface so that clothes may be arranged on the rubbing surface before being acted on by the roller, I secure to one of the sides 2 of the base one 20 end of a curved spring 26 and the pressure exerted by this spring against the side of the oscillatory frame is sufficient to hold such frame against movement, but not sufficient to permit of the free operation of 25 the frame by the operator, thus it serves as a buffer when the latter is moved in the direction of said springs.

It is thought from the foregoing description, when taken in connection with the drawings that the simplicity and advantages 30 of the construction will be apparent to those skilled in the art to which such inventions appertain without further detail description.

Having thus described the invention, what 35 I claim is:—

In a device of the class described, in combination with a base, opposed uprights extending from said base, an oscillatory frame supported by said uprights, a ribbed rubbing board beneath the frame and secured to said base, a roller carried by said frame to co-engage with said rubbing board, a pump secured to said base, connecting means for operating said pump simultaneously 45 with said roller, of a deflector member hingedly secured to the base and means secured to said pump connecting means to close the deflector upon the downward movement of said connecting means after 50 said deflector has been raised by the roller aforesaid.

In testimony whereof I affix my signature.
SIMON J. HARDING.
